UNITED STATES PATENT OFFICE.

CHARLES J. DIEGES, OF NEW YORK, N. Y.

DESIGN FOR A BADGE.

No. 39,671.

Specification for Design.

Patented Dec. 1, 1908.

Application filed October 14, 1907. Serial No. 397,451. Term of patent 3½ years.

To all whom it may concern:

Be it known that I, CHARLES J. DIEGES, a citizen of the United States, residing in the borough of Manhattan, city, county, and State of New York, have invented a new, original, and ornamental Design for a Badge, of which the following is a specification.

The nature of my design is fully represented in the accompanying drawings, to which reference is made and which shows in elevation, a badge embodying my design.

What I claim is,

The ornamental design for a badge, as shown.

CHARLES J. DIEGES.
